UNITED STATES PATENT OFFICE

2,581,039

CANDY DISPENSING TOY PUMP

Jacob H. Millstein, Jeannette, Pa.

Application February 18, 1948, Serial No. 9,139

4 Claims. (Cl. 222—368)

1

This invention relates to a candy dispensing toy and has special reference to a toy of this character resembling the dispensing pump used in gasoline dispensing stations.

One important object of this invention is to provide a novel device of this character whereby the rotation of the simulated pump handle will effect the delivery of a certain quantity of candy pellets.

Another important object of this invention is to provide a device of this kind whereby a bottle containing candy pellets may be replaceably held within an outer casing, the bottle being inverted and positioned to deliver pellets to the discharge mechanism.

A further object of the invention is to provide, in such a device, novel means for holding the bottle in place.

Still another object of the invention is to provide a novel dispensing means for such a device.

With the above and other objects in view, the invention consists in general of certain novel arrangements of details and combinations of parts hereinafter fully described, illustrated in the accompanying drawings, and particularly claimed.

In the accompanying drawings, like characters of reference indicate like parts in the several views, and

Figure 1 is a perspective view of the complete device;

Figure 2 is an elevation of one of the halves of the casing from its inside and showing a candy holding bottle therein partly in elevation and partly in section and also showing part of dispensing means in section;

Figure 3 is an elevation of the other half of the casing, viewing the same from its inside and showing part of the dispensing apparatus; and

Figure 4 is a greatly enlarged detail section on the line 4—4 of Figure 2.

In the embodiment of the invention as here shown, there is provided a casing, preferably of suitable plastic material, and having two similar halves A and B, these halves meeting, when assembled, along the line C (Figures 1 and 4).

Each of these halves is of general channel shape in horizontal cross-section, having a vertically extending web portion 10 and flanges 11 extending from the sides of the web toward the similar flanges of the other half to meet therewith when the casing is assembled. Each half of the casing has a top flange 12, carrying one-half 13 of a simulation of the dial or indicator such as is common on the top of a gasoline dispensing pump. Each half of the casing is provided with

2

10 fingers 14 which project out from the interior of the respective half and fit against corresponding portions of the interior of the opposite half, the purpose of these fingers being to ensure proper cooperation of the two halves when assembled. In the web portion of each half there is provided a window opening 15 and the flanges of each half are cut away so that when the halves are assembled there are provided window openings such as are indicated at 16 in Figure 1.

15 Projecting inwardly from each web portion is a lug 17. These lugs meet on the dividing plane of the casing and the meeting ends of the lugs are formed so that, upon the halves being assembled, there is provided a frusto-conical recess 18 having at its base a partition or shelf 19 provided with a central opening 20.

20 On the web portion of the half B and below the shelf 19 there is formed a socket 21 and opposite this socket in the web of the half A there is provided an opening 22. Supported in this socket and opening is a shaft 23 which extends outwardly through the opening 22 and is provided on its projecting end with a crank 24 simulating the crank of a gasoline pump. On the shaft 23 is fixed a drum 25 having a pocket 26 formed in its periphery. Each half of the casing carries a rib 27 which, at its inner portion, partially surrounds the drum, and from this drum surrounding portion the rib extends to one of the 25 flanges 11 of the respective member. When the two halves are assembled these ribs contact to form a delivery chute. These ribs are notched to provide an opening 28 axially aligned with the recess 18. At the end of the chute which engages the flanges 11 these flanges are notched as at 29 to form a delivery opening and on the outside of the casing are small ribs partially surrounding the delivery opening and forming a species of delivery cup 30.

30 The candy to be distributed by this device is held in a bottle 31, the body of which is embraced by the upper part of the casing. This bottle is preferably made of glass or of transparent plastic material so that the candy contents can be seen through the windows in the casing. This bottle has square shoulders 32 which, when the bottle is in position, rest on the lugs 17. This bottle also has a flaring frusto-conical neck 33 which is received in the recess 18. The internal bore of this neck is preferably the same as that of the opening 28 in the delivery chute so that candy from the bottle can flow through this opening and be received in the pocket 26 as the drum is rotated and thus be de-

livered to the outlet portion of the chute as rotation thereof is continued.

It is to be understood that the two halves of the casing may be permanently or separably connected. In case the halves are permanently connected the device cannot be refilled with candy, but if the halves are separably connected they may be separated and the empty bottle removed and replaced by a full one, after which the halves may again be connected.

In order to make the simulation to a gasoline pump more complete, the toy is provided with a simulated hose 34, nozzle 35 and nozzle holding hook 36.

What is claimed is:

1. In a candy dispensing toy, a housing casing consisting of two separable sections of like transverse configuration to confront each other in connected registration and provide a hollow housing, a candy-holding bottle having a neck zone mounted within said casing in inverted position and housed thereby with the bottle opening downward, said sections having internal formations for supporting the bottle in such position, a delivery chute beneath said bottle, a drum in said chute having a candy-receiving pocket in its periphery, the axis of said drum intersecting the division line between the casing sections, said chute having an opening in registration with the bottle opening, and means extending axially through the drum and supported by both sections, said means being mounted for exterior rotation to thereby permit drum rotation to move the drum pocket into and out of registration with

the chute opening and to deliver the pocket content into the chute.

2. A toy as in claim 1 characterized in that the means includes a removable shaft extending axially of the drum with the shaft extending through the face of one section and removably supported in a bearing carried by the internal face of the other section to thereby permit separation of sections for substitution of bottles.

3. A toy as in claim 1 characterized in that the bottle-supporting formations include spaced elements carried by an inner face of each section and positioned in confronting relation and relative to one another to thereby produce a receiving recess for the neck zone of the positioned bottle.

4. A toy as in claim 3 characterized in that the bottle is formed with shoulders in addition to said neck zone, the elements comprising the supporting formations being formed to cooperate with the bottle neck zone, the cooperation relation being of interlocking frusto-conical form.
